CLAIM

I claim the ornamental design for the lifting lug for an engine-driven operating machine, as shown and described.

DESCRIPTION

FIG. 1 is a front perspective view of the lifting lug for an engine-driven operating machine embodying my design; FIG. 2 is a front elevational view of the lifting lug for an engine-driven operating machine as shown in FIG. 1; FIG. 3 is a rear elevational view of the lifting lug for an engine-driven operating machine as shown in FIG. 1; FIG. 4 is a top plan view of the lifting lug for an engine-driven operating machine as shown in FIG. 1;

FIG. 5 is a right side elevational view of the lifting lug for an engine-driven operating machine as shown in FIG. 1; FIG. 6 is a left side elevational view of the lifting lug for an engine-driven operating machine as shown in FIG. 1; and, FIG. 7 is a front elevational view of the lifting lug for an engine-driven operating machine as shown in FIG. 1 showing the collapsed position of the lifting lug.

The broken line showing is for illustrative purposes only and forms no part of the claimed design.
